Dec. 1841

Elemin F. Ney. of Lowell, Mass.
Assign to

The Lowell Manufacturing Company.

Letters Patent No. 1841 Dated Nov 10th 1863

Design for a Carpet Pattern.

The schedule referred to in these Letters Patent and making part of the same.

To all whom it may concern:

Be it known that I, Elemin F. Ney, of Lowell, in the County of Middlesex and State of Massachusetts, have originated and designed a new Pattern for Carpets or other fabrics, of which the following is a full, clear and exact description, reference being had to the accompanying drawings, making part of this specification.

A, is a set figure composed of a number of blocks arranged as shown in the drawings. Figure B is similar to A.

Extending from corner 1 to corner 2, is the broad band C, the interior of which is composed of combinations of short lines and blocks.

D and E, are bands, similar to C, running at right angles with C, and parallel with each other.

2

Des. 1841

In corners 3 and 4, are shown sections of bands similar to C. When the design is matched the band C, and the bands D and E, and their continuations, intersect at regular intervals. The remainder of the design consists of sprigs attached to the band beforementioned.

The colors employed for the different portions of the design may be varied to suit the taste and wish of the manufacturer.

~ Claim. ~

What I claim as my invention and design to secure by Letters Patent, is the Design or Pattern for Carpets or other fabrics, herein set forth.
